CONTAINER

Cleon M. Hannaford, Toledo, Ohio; Marie L. Hannaford executrix of said Cleon M. Hannaford, deceased

Application April 8, 1941, Serial No. 387,477

1 Claim. (Cl. 65—13)

The invention contemplates a drinking container having a greater area at its base than at its drinking edge and when not in use having its drinking edge suspended in air rendering the same more stable and sanitary.

The invention embraces a hollow receptacle adapted for drinking purposes having an open end of smaller diameter than its closed end and when placed in a position to prevent the ingress of foreign substances to the inner compartment the open end is suspended in air.

The invention includes as one of its objects a drinking container which is very stable having a comparatively low center of gravity either empty or filled with fluid by providing a base which is of greater area than its drinking end.

A still further object of the invention is the provision of a drinking vessel of frusto-conical formation having a base of larger diameter than that of its drinking end and its outer intermediate surface being provided with a peripheral ridge.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a side elevational view illustrating a drinking receptacle or container and a form of support therefor of my invention;

Figure 2 is a top plan view of the container and support illustrated in Figure 1;

Figure 3 is a front elevational view of the arrangement shown in Figure 1 with the drinking receptacle shown partly in section;

Figure 4 illustrates a modified form of drinking receptacle of my invention;

Figure 5 illustrates a modified form of drinking receptacle support forming a part of my invention;

Figure 6 is a top plan view showing another form of supporting means for receiving a plurality of drinking receptacles in stored or normally inverted positions;

Figure 7 is a vertical sectional view taken substantially on the line 7—7 of Figure 6.

While I have illustrated forms of my invention embodied in drinking receptacles and supports therefor, it is to be understood that I contemplate the application of my invention to con-

tainers and supports therefor for other purposes wherever the same may be found to have utility.

Referring to the drawing in detail and first with respect to the form of the invention shown in Figures 1 to 3 inclusive, the receptacle 10 is illustrated in stored or normally inverted position and being carried in a support 12. The drinking receptacle 10 is of frusto-conical formation preferably having a gradual and uniform flare from its open end toward its closed end in which base 13 is of greater dimension or diameter than that of the lip or pouring portion 14, the side walls 15 being of tapered configuration as illustrated. The side walls and base of the receptacle are preferably made of uniform thickness as shown in Figure 3, although a varying thickness of walls or base for the receptacle may be used without departing from the spirit of the invention.

20 A form of support 12 illustrated in Figures 1 to 3 is preferably formed of wire having a circular or annular portion 17 to receive the drinking receptacle 10 in inverted position as shown in Figures 1 and 3. The wire extends rearwardly 25 of the receptacle 10 and has its extremities formed into curved configuration as shown at 19 and 20 in Figure 3 to form eyes 21 adapted to receive retaining screws 22 for securing the support to a wall 23 or other suitable surface. 30 The portions 24 and 25 of the support are preferably bent in opposite directions as shown in Figures 1 and 3 in order to impart stability to the support.

It is contemplated that the container be stored in the support, and therefore, there are several 35 advantages in the applicant's invention when the container 10 is retained in support 12, the mouth or lip portion 14 is suspended in air and entirely out of contact with any surface such as 40 a sink, drain board or shelf, therefore the drinking or pouring edge of the container will not become contaminated with foreign substances. Furthermore, the receptacle being in inverted position there is no possibility of the settling of 45 dust, dirt and other foreign matter within the receptacle, thus giving greatly improved sanitation for receptacles of this character.

When the drinking receptacle 10 is in position 50 of use, it is noted that the base portion 13 is of comparatively large area so that the lower portion of the receptacle contains more fluid than the upper portion resulting in a lowering of the center of gravity of the receptacle either when it is empty or filled with fluid. This is a distinct advantage 55 because it requires considerably more force to up-

set or turn over a receptacle of this character as compared with a conventional receptacle where the mouth portion of the glass is of greater area than the base and the present structure is therefore relatively stable as compared with the conventional containers heretofore in use.

Figure 4 illustrates a modified design of the container wherein the container 10' is formed with a peripheral bead or ridge 27 which may be proportioned to engage the annular or ring-shaped portion of the support 17 when the receptacle is placed therein. In the arrangement shown in Figure 4 with the container in use, the bead 27 provides a surface which may be grasped by a person using the container to enhance the effectiveness of the grip upon the container.

Figure 5 illustrates a form of support 12' fabricated from wire or the like suitable for accommodating several containers of the type shown in Figure 1 and Figure 4. The central portion 30 of the support 12' is configurated so as to receive a comparatively large drinking receptacle while the loop portions 31 are arranged to receive smaller receptacles of the same general character. The support 12' has the same construction of projections 24' for securing the container support to a suitable surface. It is to be noted that in the forms of support shown in Figures 1 and 5 they are composed of a single piece of wire bent to the proper configuration, thus simplifying the manufacture of this type of support.

As illustrated in Figures 6 and 7, there is provided another form of support for carrying a plurality of containers of my invention, the support is preferably made in one piece and in the form of an inverted cup-like member or inverted serving tray 35 having a horizontal uniplanar portion 36 bounded by a depending peripheral wall 37. This support may be of molded material or may be fabricated of sheet metal or other inex-

pensive material. The uniplanar portion 36 is perforated or provided with openings of a diameter suitable to receive the containers 10 without permitting the containers to protrude through the uniplanar portion to a distance where their lower or mouth portions 14 could extend below the lower edge 38 of the wall 37. By this means the support 35 elevates the containers so that the mouth portions thereof never come in contact with surfaces which may contaminate the pouring or drinking edges of the receptacles. The supporting structure 35 in addition can be very effectively used as a serving tray when the containers are filled with liquid by utilizing the inner face of the uniplanar portion 36 as a carrying surface in view of the fact that the openings formed thereon are of smaller size than the base of the containers.

The several forms of containers of my invention illustrated in the drawing may be fabricated of any suitable material as for example, glass, any of the plastics or phenol formaldehyde products or any material which may be molded or worked to the proper configuration.

It is apparent that, within the scope of the invention, modifications and different arrangements may be made other than is herein disclosed, and the present disclosure is illustrative merely, the invention comprehending all variations thereof.

What I claim is:

A drinking vessel of hollow formation having a closed end; the main body portion of said receptacle of substantially uniform thickness; the open end being of smaller diameter than the closed end; the side walls flaring outwardly from the open end to the closed end; and a peripheral ridge formed on said side walls intermediate said ends.

CLEON M. HANNAFORD.
